UNITED STATES PATENT OFFICE.

WILLIAM R. DEAN, OF FORT PIERRE, SOUTH DAKOTA.

FUNNEL.

Application filed May 2, 1922. Serial No. 557,941.

To all whom it may concern:

Be it known that I, WILLIAM R. DEAN, citizen of the United States, residing at Fort Pierre, in the county of Stanley and 5 State of South Dakota, have invented certain new and useful Improvements in Funnel, of which the following is a specification.

This invention relates to an improved 10 funnel and seeks, as one of its principal objects, to provide a device of this character embodying an indicator whereby, when filling a vessel or container, in the practical use of the funnel, the common experience of running the vessel or container over may be 15 obviated.

A further object of the invention is to provide a funnel having a float so mounted that when a vessel or container is filled, the 20 float will be raised for indicating that the filling operation should be stopped.

And the invention has as a still further 25 object to provide a funnel well adapted for general use and so constructed that the funnel cannot tilt under the weight of the liquid therein to spill the liquid.

Other and incidental objects will appear hereinafter.

In the drawing:

30 Figure 1 is a perspective view of my improved funnel showing the device in connection with a barrel which is illustrated in dotted lines,

35 Figure 2 is a vertical sectional view through the device, and

Figure 3 is a top plan view of the funnel.

In carrying the invention into effect, my 40 improved funnel is formed with a bowl 10 which is preferably provided with a flat back wall 11, while the front wall of the bowl is, as shown in Figures 1 and 3, curved and extended to form the side walls which join with the back wall. Depending from the front and side walls of the bowl is a 45 curved base flange 12 and mounted upon the back wall is a handle 13. Secured to the several walls of the bowl is a bottom wall 14 which, as shown in Figure 2, slopes toward the back wall of the bowl and connected to 50 said bottom wall is a discharge pipe 15 slightly spaced forwardly with respect to the plane of the back wall of the bowl. At a suitably spaced point below said bottom wall, the discharge pipe is notched at its 55 forward side to provide a discharge opening 16 and mounted in the pipe at the lower

end of said notch is a partition or closure 17. A float chamber 18 is thus defined at the lower end portion of the pipe, the pipe being open at its lower end, and leading upwardly through the pipe from said chamber is a combined guide and vent tube 19 soldered or otherwise secured to the back wall of the bowl. Freely mounted in the chamber 18 is an appropriate float 20 and connected to said float is a rod or wire 21 which extends upwardly through the tube 19 and is provided at its upper end with a loop or head 22 adapted to engage the upper end of said tube for limiting the float against downward displacement from said chamber. Formed in the chamber at its rear side is a longitudinally directed slot 23 and extending from the float is a pin 24 which projects freely through said slot, locking the float 75 against rotation so that the loop 22 at the upper end of the float rod will always be held in a position out of the way parallel to the back wall of the bowl 10.

The present funnel is particularly designed for filling barrels, tanks, or the like, and in the drawing, I have accordingly shown the device in connection with a conventional metal barrel 25. As illustrated, the discharge pipe 15 is positioned through 80 the filling opening of the barrel so that the base flange 12 of the funnel rests against the upper end of the barrel. Accordingly, this flange will firmly support the funnel against tilting under the weight of the liquid within 85 the funnel so that spilling of the liquid from this cause will be prevented. As the liquid is poured into the bowl 20 air may, as will now be seen, escape through the tube 19 so that the barrel will be vented through said 90 tube and should the device be used in connection with a container having a vent opening only large enough to snugly accommodate the discharge pipe 15, the container will, nevertheless, be amply vented through 95 said tube. When the barrel is nearly filled and the liquid within the barrel reaches the float 20, the float will be lifted for lifting the float rod and thus indicating the level of the liquid in the barrel and that the filling operation should be retarded or stopped. I accordingly provide a funnel of particularly 100 efficient construction and a device adapted for a wide range of use.

Having thus described the invention, what 110 is claimed as new is:

1. In a funnel, the combination of a bowl

- having a flat back wall and provided with a reduced discharge pipe of uniform diameter leading from the bowl at one side thereof adjacent said wall, the discharge pipe being
- 5 cut away at one side to provide a discharge opening, a partition in the discharge pipe at the lower end of said opening defining a float chamber at the lower end portion of the pipe, a tube mounted against said back wall to extend downwardly within the discharge 25 pipe through said partition into said float chamber, a float mounted within the chamber, a rod extending from the float upwardly within said tube and provided at its upper end with a head, the wall of said chamber 30 having a slot therein, and a pin extending from the float freely through said slot for locking the float against rotation whereby to maintain the head of said rod in a pre-determined position with respect to the back 35 wall of the bowl.
- 10 to extend downwardly within the discharge pipe through said partition into said float chamber, a float mounted within the chamber, and a rod extending from the float upwardly within said tube.
- 15 2. In a funnel, the combination of a bowl having a flat back wall and provided with a reduced discharge pipe of uniform diameter leading from the bowl at one side thereof adjacent said wall, the discharge pipe being
- 20 cut away at one side to provide a discharge

In testimony whereof I affix my signature.

WILLIAM R. DEAN. [L.S.]
